Smith Cram, of Long, County & State of New York.

Letters Patent.

The subject referred to in these Letters Patent and making part of the same containing a description in the words of the said Smith Cram himself of his improvement in the method of taking a train of cars over eminences by locomotive engines, --

Be it known that I, Smith Cram, of New York in the County of New York, and State of New York, have invented a new and useful improvement in the method of taking a Train of cars over eminences by locomotives, which is described as follows, reference being had to the annexed drawings of the same, making part of this specification.

The method of said Cram consists chiefly in the construction of the wheels of the locomotive to be used and the track or tracks on which it is to move, and track up the eminences is to be constructed parallel with the track on which the train of cars is to move. The tracks of the locomotive are made in effect as two rocks such as are represented at A. & B. in the Drawings, into which teeth C. formed in and projecting from the arms or peripheries of the wheels may firmly take the weight of the locomotive being borne upon, the flat part of such track construction of flat bars, as far apart as the width of the teeth each bar being about one inch and a half wide and the teeth of sufficient width to have the strength in them necessary to take up the ascending or descending train when working against the teeth of the rock, which consist of small bars several between said flat bars is otherwise.

This locomotive being attached laterally or otherwise to the train and put in motion, takes it up or down by the action of the teeth on the wheel of the locomotive, upon the track constructed as aforesaid, and to prevent the locomotive from running back when ascending or running down steeply when descending there are catches constructed to take

into the teeth in said racks, or into the teeth in said shay in any convenient manner, and the said shay bram to prevent cars from being thrown off the track suddenly, the track so far above ground on the inside of the tracks as to prevent a car loosely fixed to the locomotive or cars on each side thereof and near the wheels, to take under the track plates, so that the locomotive or car cannot be thrown off without tearing up the rails or track plates.

And the said shay to prevent the vibrating or swinging of the cars when in speed, fixes horizontal wheels to run against the inside of the rails or plates in the most convenient and proper manner.

And what the said bram claims as his invention and desire to have by Letters Patent, is the method of forming the racks as before specified and described for taking trains of cars over embankments, and boats or barges from one level to another in canal navigation.
